UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 28, 1926. Serial No. 118,954.

My invention relates to railway traffic controlling apparatus, and particularly to apparatus of the type comprising train carried governing means controlled by energy received from the trackway. More particularly my present invention relates to the train carried portion of such apparatus.

In at least one form of traffic controlling apparatus of this type, the governing mechanism on the train requires the continuous supply of energy from the trackway to prevent an automatic application of the brakes. When this supply is interrupted the brakes are applied unless the engineman acknowledges this change by suitable action. One object of my invention is to provide apparatus which will require the engineman to take such acknowledging action at regular intervals of train travel to prevent an application of the brakes when such energy is not supplied to the train.

The present application is a continuation-in-part of my co-pending application Serial #25538, filed April 24, 1925 for railway traffic controlling apparatus, in so far as the subject matter common to the two is concerned.

I will describe one form of train carried governing mechanism embodying my invention, and will then point out the novel features thereof in claims.

The accompanying drawing is a view, partly diagrammatic, illustrating one form of apparatus embodying my invention.

Referring to the drawing, the reference character E designates a magnet valve comprising a stem 2 provided with an armature 84 and a winding 1. When winding 1 is energized the stem 2 occupies its upper or normal position and fluid pressure is admitted from a suitable source not shown in the drawing, through pipe 18 to pipe 11. When winding 1 is de-energized, however, the stem 2 drops to its lower position, blanking pipe 18, and connecting pipe 11 with pipe 19. The lower end of stem 2 projects below the bottom of the winding 1 as illustrated at 5, for a purpose which will be explained hereinafter.

Associated with magnet valve E is an application valve G comprising a chamber 21 containing a reciprocable piston 22 carrying a valve stem 23. Chamber 21 under piston

22 is connected with pipe 11 and a reservoir 6. Valve G controls the usual brake applying mechanism on the train by means of a pipe 33 which is normally supplied with a fluid, usually air, under pressure and arranged to apply the brakes when the pressure in such pipe is reduced. Pipe 33 is connected, through valve J, with pipe 25 which is blanked when valve stem 23 of valve G occupies its upper position.

When winding 1 is energized, then, so that valve stem 2 occupies its upper or normal position, fluid pressure from pipe 18 is supplied to reservoir 6, and to chamber 21 of valve G. The pressure in chamber 21 raises piston 22, blanking pipe 25 and connecting a reservoir 82 with atmosphere through port 24.

When winding 1 becomes de-energized however, so that stem 2 moves to its lower position, pipe 18 is blanked, and the pressure in reservoir 6 and chamber 21 is slowly vented to atmosphere through pipe 19 and an audible signal here shown as a whistle 83. The engineman is therefore warned of the change of condition of the train carried apparatus.

After a time interval the pressure in chamber 21 is so reduced that valve G reverses, causing piston 22 to move to its lower position, thereby connecting pipe 25 with the reservoir 82. As a result of this connection, the pressure in pipe 33 is reduced to cause an automatic application of the brakes.

An application of the brakes when valve G is operated can be prevented by proper operation of the engineman's acknowledging valve K. This acknowledging valve controls a valve J comprising a chamber 30 containing a piston 28 carrying a plunger 32 and biased to a lower position by spring 14. When handle 34 of valve K is in the position shown in the drawing, a reservoir 36 is charged with fluid pressure through pipe 18^a, from a suitable source not shown in the drawing. When valve K is operated, pipe 18^a is blanked, and reservoir 36 is connected with chamber 30 of valve J by means of pipe 31. Piston 28 therefore rises, causing plunger 32 to blank pipe 33. This motion of plunger 32 also opens a valve 27 which is normally held closed by a spring 13. When valve 27 is open fluid pressure is supplied

from a suitable source not shown in the drawing, through pipe 18^b, to pipe 25. The wall of chamber 30 is provided with a restricted orifice 30^a so that after a time interval following operation of valve K to lift piston 28, the pressure in reservoir 36 and chamber 30 is so reduced by leakage through port 30^a that piston 28 and plunger 32 return to their lower positions, again connecting pipe 33 with pipe 25, and closing valve 27. The parts are so proportioned that when valve K is operated, piston 28 remains in its upper position for a longer interval of time than does piston 22 of valve G after valve E is reversed.

Valve E is controlled by a train carried relay which, for convenience, I will call a "main relay". This relay is controlled by means forming no part of my present invention, and is omitted from the drawing for the sake of simplicity, in such manner that when traffic conditions in advance of the train are safe relay A is energized, but when traffic conditions in advance of the train are dangerous, relay A is deenergized.

As shown in the drawing, relay A is energized. Current then flows from one terminal B of a suitable source of energy not shown in the drawing, through wire 38, front contact 39 of relay A, wires 40 and 41, winding 1 of valve E and back to terminal C of the same source. Winding 1 is therefore energized and valve E is in its normal position. Fluid pressure is therefore supplied from pipe 18 to chamber 21 of valve G and reservoir 6 is charged with air pressure. Stem 23 of valve G is in its upper position so that pipe 25 is blanked, and reservoir 82 is connected with atmosphere. With relay A energized current also flows from terminal B through wire 38, front contact 39 of relay A, wires 40 and 43, indicator lamp 15 and wire 45 back to terminal C. The engineman is informed, by the lighting of the lamp 15, that he is proceeding under safe traffic conditions.

I will next assume that relay A becomes de-energized, as when the train enters dangerous territory. The opening of the front contact 39 of the relay interrupts the circuit for lamp 15 and the closing of back contact 39 completes a circuit for lamp 17 which may be traced from terminal B, through wire 38, back contact 39 of relay A, wire 46, lamp 17 and wire 45 back to terminal C. Lamp 17 therefore becomes lighted to inform the engineman that he is proceeding under dangerous traffic conditions. The de-energization of relay A also de-energizes winding 1 of valve E. This valve therefore reverses and fluid pressure in chamber 21 of valve G and in reservoir 6 is slowly vented to atmosphere through the whistle 83. The operation of the whistle calls the attention of the engineman to the

fact that he must acknowledge in order to prevent an automatic application of the brakes. Assuming that the engineman does not acknowledge, after the expiration of a time interval the stem 23 of valve G drops, thereby connecting pipe 25 with reservoir 82 and causing a reduction in the pressure of pipe 33 which will result in an automatic application of the brakes.

It should be noted that the whistle sounds as long as fluid pressure from reservoir 6 and chamber 21 is being vented to atmosphere, that is, this whistle sounds for the entire period during which the engineman can acknowledge.

If the engineman acknowledges by operating valve K prior to the operation of valve G, piston 28 of valve J, moves to its upper position blanking pipe 33 and opening valve 27 to connect pipe 18^b with pipe 25. At the expiration of the time interval required to empty reservoir 6, valve G reverses, but pipe 25 is now connected with pipe 18^b so that the only result of the reversal of valve G is to charge reservoir 82 with fluid pressure. Subsequent to the reversal of valve G, the reduction of pressure in reservoir 36 due to orifice 30^a permits valve J to return to its normal position thereby reconnecting pipe 33 with pipe 25 and blanking pipe 18^b. As a result of this connection between pipe 33 and pipe 25 the pressure in pipe 33 is not reduced because pipe 25 and reservoir 82 have previously been charged with fluid pressure, and the brakes are not applied. The train is therefore permitted to proceed without interference.

It will therefore be seen that if the engineman acknowledges by operating valve K during the interval of time that whistle 83 is operating, an automatic application of the brakes is prevented.

I will now assume that relay A again becomes energized, as by a change from dangerous to safe traffic conditions. Winding 1 then becomes energized over front contact 39 of relay A, lifting piston 22 of valve G and charging reservoir 6 with fluid pressure. This operation of valve G again vents reservoir 82 to atmosphere so that the apparatus is placed in condition to cause an automatic application of the brakes should relay A again become de-energized. The energization of relay A also energizes lamp 15 as explained hereinbefore.

The train is also provided with an intermittent device designated in general by the reference character D and comprising a ratchet wheel 50 rigidly secured to a shaft 49 supported in suitable bearings not illustrated in the drawing. An arm 52 is arranged to rock loosely on shaft 49 and is connected by means of a link 53 with a reciprocating part of the train, as the locomotive valve gear. Pivoted to arm 52 at point 130

55 is a pawl having a tip 56 adapted to engage the teeth of ratchet wheel 50 and provided on its other end with an armature 57. Carried on arm 52 is also a magnet 58 arranged when energized to attract armature 57 downwardly, thereby swinging the tip 56 of the pawl free from the teeth in ratchet 50. It will be clear from the drawing that when the locomotive is in motion arm 52 will 10 swing through its path once for each unit of distance travelled and that if magnet 58 is de-energized this to and fro motion transmitted by pawl 54, will advance ratchet 50 in a counter clockwise direction one tooth 15 for each reciprocation of arm 52 and that rotation of ratchet wheel 50 will therefore measure the distance travelled by the train. If, however, magnet 58 is energized, tip 56 of pawl 54 is swung free of the teeth of ratchet wheel 50 and the reciprocating motion of arm 52 is not effective to rotate the wheel. Rigidly secured to shaft 49 is a pinion 51 which meshes with a gear 59 supported by shaft 79 journalled in suitable bearings not shown in the drawing. Supported also on shaft 79 and fixed to gear 59 is a cam 60 having a cam swell y . An arm 62 is pivoted at point 61 and bears against cam 60. When cam swell y engages arm 62 the right-hand end of this arm is moved upwardly to engage the tip of stem 2 of valve E and moves this member to its upper position. At the same time contact 78-63-77 is opened and contact 66-63-67 is closed. 20 The reference character H designates a slow-releasing relay having a pick-up circuit and a stick circuit. The pick-up circuit may be traced from terminal B, through front contact 64 of relay A, wires 65 and 65^a, contact 66-63-67, wires 68, 69 and 70, winding of relay H, and wire 71, back to terminal C. This circuit is closed only when relay A is energized and lever 62 is in its upper position, under which conditions relay H becomes energized. The stick circuit is then closed, which circuit is from terminal B, through front contact 64 of relay H, wires 65 and 72, front contact 73 of relay H, wires 74 and 70, winding of relay H, and 25 wire 71 to terminal C. Relay H thereafter remains in its energized condition as long as relay A remains energized.

When relay H is energized and lever 62 is in its lower position a circuit is closed from terminal B, through front contact 64 of relay A, wires 65 and 72, front contact 73 of relay H, wires 74 and 69, contact 77-63-78, wire 75, magnet 58, and wire 76, to terminal C. When this circuit is closed magnet 58 is energized and pawl 54 is swung out of engagement with the teeth of ratchet wheel 50 so that oscillation of arm 52 has no effect upon the ratchet wheel.

When the train is proceeding under safe traffic conditions, relay A is energized. Re-

lay H is then held in its energized condition by its stick circuit, and magnet 58 is energized. Pawl 54 is therefore swung out of engagement with the teeth of ratchet wheel 50. Cam 60 is, under these conditions, in 70 such position that cam swell y is in the position shown in solid lines in the drawing. If now, relay A becomes de-energized, as by the entrance of the train into dangerous territory, the consequent de-energization of 75 magnet E reverses valve G after a time interval and applies the brakes as hereinbefore described unless the engineman acknowledges. The opening of front contact 64 of relay A also opens the stick circuit for 80 relay H, which relay becomes de-energized. The opening of front contact 73 of relay H in turn de-energizes magnet 58, thereby allowing the tip 56 of pawl 54 to drop down and engage ratchet wheel 50. The reciprocation of arm 52 then advances ratchet wheel 56 and cam 60, moving cam swell y in a clockwise direction. After the train has travelled a predetermined distance, cam swell y is moved into a position in which 90 it engages lever 62, swinging this lever upward. Lever 62 then engages the tip 5 of stem 2 of valve E and moves this member upwardly to charge reservoir 6 from pipe 18 and to restore valve G to its normal position. 95 When the motion of cam 60 has moved the swell y past lever 62 the lever again drops, allowing stem 2 to again assume its lower position and the engineman is again required to acknowledge to prevent an automatic brake application. 100

It should be noted that when the train proceeds under dangerous traffic conditions lamp 17 is continuously lighted, but each time stem 2 of valve E is raised reservoir 6 105 is charged with fluid pressure. When the stem 2 has returned to its lower position, the fluid pressure in the reservoir operates whistle 83 for a time interval during which the engineman must acknowledge to prevent 110 an automatic application of the brakes.

If proper acknowledgment is made, the train may proceed, but cam 60 is continuously rotated and after the train has traversed a predetermined distance, cam swell y 115 again engages lever 62 to operate valve E, and the engineman is again required to acknowledge to prevent a brake application. It is plain that by properly proportioning the various parts, acknowledgment may be 120 required by operation of the device D at any desirable intervals of train travel.

The operation of latching up the intermittent device D is as follows:

I will assume that relay A is de-energized 125 and the intermittent device is operating with the cam swell y in some position of its path such as indicated by the dotted line at x . If, now, relay A becomes energized as by a change in traffic conditions from dangerous 130

to safe, the magnet 1 of valve E will become energized and the parts controlled by this valve will be restored to their normal condition as described hereinbefore. The closing 5 of front contact 64 does not complete the pick-up circuit for relay H however, this circuit being open at contact 66-63-67. The intermittent device D therefore continues to operate until cam swell y moves lever 10 62 upward. Relay H then becomes energized. When cam swell y moves past lever 62 the lever drops down, opening the pick-up circuit for relay H and closing the stick circuit at contact 78-63-77. The closing of 15 contact 78-63-77 also completes the circuit for magnet 58 and so pawl 54 is disengaged from the ratchet wheel 50. It will thus be plain that cam swell y remains in the position shown in solid lines in the drawing as 20 long as relay A is energized.

From the foregoing description it will be obvious that the engineman is required to acknowledge to prevent a brake application when the train moves into a stretch of track 25 where traffic conditions are unsafe from a stretch where the conditions are safe, and furthermore, such acknowledgment is again required each time the train has traversed a predetermined distance, the first of these 30 distances being measured from the point at which relay A becomes de-energized.

Although I have herein shown and described only one form of train carried governing mechanism embodying my invention, 35 it is understood that various changes and modifications may be made therein within the scope of the appended claims without departing from the spirit and scope of my invention.

Having thus described my invention, what I claim is:

1. In combination on a train, an automatic braking mechanism comprising a brake pipe effective to apply the brakes when vented to atmosphere, a device controlled in accordance with the distance traversed by the train, a valve normally connected with said pipe and periodically opened by said device under unsafe traffic conditions, and manually op-

erable means for disconnecting said pipe 50 from said valve.

2. In combination, on a railway train, automatic brake applying apparatus comprising a valve arranged when opened to cause an application of the brakes, means for opening said valve for a time interval when the train enters unsafe territory, and means arranged to move in accordance with the distance travelled by the train for again opening the valve for a time interval after the 55 train has subsequently travelled a predetermined distance, and manually operable means effective during said time intervals to prevent an automatic brake application.

3. In combination, on a train, a lever normally occupying one position but arranged to be temporarily moved to a different position each time the train moves a predetermined distance in unsafe territory, a valve arranged to be closed under safe traffic conditions and to apply the brakes when opened, manually operable means effective to prevent such automatic application of the brakes when said valve is open, means for opening said valve for a time interval when the train 70 enters dangerous territory and means for thereafter causing said valve to be opened when said lever is in said different position.

4. In combination, on a railway train, a relay arranged to be energized or de-energized according as traffic conditions in advance of the train are safe or unsafe respectively, a slow releasing relay, a member arranged to be moved repeatedly through the same cycle of positions in accordance with the distance travelled by the train, a pick-up circuit for said slow releasing relay closed when said member occupies a predetermined position, means for subsequently closing a stick circuit for said slow releasing relay 80 when said member moves out of such predetermined position, and means effective when said first relay and said slow releasing relays are both energized for maintaining said member fixed in position irrespective of the 85 distance travelled by the train.

In testimony whereof I affix my signature.
LLOYD V. LEWIS.
